United States Patent Office.

SAMUEL SAGE COE, OF CLEVELAND, OHIO.

Design No. 3,963, dated April 12, 1870.

DESIGN FOR AN ADJUSTABLE COUNTING-HOUSE CALENDAR.

The Schedule referred to in these Letters Patent and making part of the same

Be it known that I, SAMUEL SAGE COE, of Cleveland, in the county of Cuyahoga and State of Ohio, have invented a new and improved Design for a Perpetual Calendar, of which the following is a specification.

Drawings.

Figure 1 is a front view of the calendar.

Figures 2 and 3, detached sections.

Like letters of reference refer to like parts in the different views.

Object of Invention.

This invention relates to the form and configuration of a design for an advertising perpetual calendar, as hereinafter described.

In fig. 1—

A represents the face of the device, which, as will be observed, is an oblong square, terminating at the top with a loop, whereby it is hung up for observation.

Midway the length of the face, and transversely thereto, is cut a slot, B, through which may be seen the abbreviations of the days of the week, and which are read lengthwise in the slot from left to right. Said abbreviations are arranged upon a roller, and which may also be read around the same from Monday to Sunday, in the same order as they are read transversely through the slot.

C, fig. 3, is a disk, pivoted at the center to the back of the calendar. On the margin of said disk is displayed the abbreviation of the names of the months, and which may be read through an opening, D, in the face of the device.

The operation of this device is as follows:

Let it be supposed that the month is January. Said month will appear in the opening D on turning the disk by the finger-piece E. Let it also be supposed that the month commenced on Monday. Now, on

turning the roller by means of the finger-pieces F, the day, Monday, will appear at the extreme left of the slot B, the other days ranging in order along to the right. It will be seen that Monday is the first, Tuesday the second, Wednesday the third, &c., and so on to the end of the week and to the end of the month, the figures below the slot indicating each day.

It will be seen that the month ends on Wednesday; hence Thursday should be the first day of February instead of the fourth, as shown by the figure immediately below. To correct this error, the roller is turned until the day Thursday appears at the extreme left end of the slot, which will be immediately over the figure 1, the correct date. The disk is turned until the month February appears in the opening, as shown in fig. 2, and so on for each month in the year.

On the face of the calendar above the slot is displayed the following, viz:

"Perpetual Calendar for the Cleveland Insurance Company, capital \$500,000, chartered A. D. 1830."

Below the slot are arranged the dates of the month, and in the lower right-hand corner is displayed the following:

"For insurance in this company apply to_____, agent," all of which, together with its construction, constitutes a design for an advertising perpetual calendar.

Claim.

What I claim as my invention, and desire to secure by Letters Patent, is—

The herein-described form and configuration, as a design, for the advertising perpetual calendar specified.

SAMUEL SAGE COE.
